United States Patent Office

Des. 214,599
Patented July 1, 1969

214,599

SOAP BAR

William C. Sizer, Box 832, Minneapolis, Minn. 55440

Filed May 27, 1968, Ser. No. 12,088

Term of patent 14 years

Int. Cl. D28—99

U.S. Cl. D73—1

FIG. 1

FIG. 2

FIG. 4

FIGURE 1 is a top plan view of a soap bar showing my new design;

FIGURE 2 is a side elevational view of the design;

FIGURE 3 is a vertical cross-sectional view of the design; and

FIGURE 4 is a bottom plan view of the design.

I claim:

The ornamental design for a soap bar, substantially as shown.
